US00D880568S

(12) **United States Design Patent** (10) **Patent No.:** **US D880,568 S**
(45) **Date of Patent:** **** Apr. 7, 2020**

(54) **CAMERA MOUNT**

- (71) Applicant: **Wisconsin Archery Products LLC**, Mukwonago, WI (US)
- (72) Inventors: **Timothy M. Gorsuch**, Mukwonago, WI (US); **Steven K. Hansen**, Port Washington, WI (US)
- (73) Assignee: **WISCONSIN ARCHERY PRODUCTS LLC**, Mukwonago, WI (US)
- (**) Term: **15 Years**
- (21) Appl. No.: **29/585,319**
- (22) Filed: **Nov. 22, 2016**
- (51) LOC (12) Cl. **16-05**
- (52) USPC **D16/242; D25/126; D26/93; D11/130.1; D8/382**

(58) **Field of Classification Search**

USPC D8/354, 355, 363, 373, 382-383, D8/394-396; D14/224, 229, 238, 251, D14/447, 451, 457; D16/237-250; D11/130.1; D24/128; D26/93

CPC E04H 12/2215

CLAIM

The ornamental design for a camera mount, as shown and described.

DESCRIPTION

FIG. 1 is a perspective view of a camera mount of the present invention;

FIG. 2 is a first side view of the camera mount of the present invention;

FIG. 3 is a second side view of the camera mount of the present invention;

FIG. 4 is a third side view of the camera mount of the present invention;

FIG. 5 is a fourth side view of the camera mount of the present invention;

FIG. 6 is a top view of the camera mount of the present invention; and,

FIG. 7 is a bottom view of the camera mount of the present invention.

The broken lines in the drawings depict environmental structure and form no part of the claimed design. The camera mount is shown with a symbolic break in its length. The appearance of any portion of the article beyond the break line forms no part of the claimed design.
